Application filed July 22, 1896. Serial No. 600,171. Term of patent 14 years.

To all whom it may concern:

Be it known that I, ISAAC E. PALMER, of Middletown, in the county of Middlesex and State of Connecticut, have invented and produced a new and original Design for Hammocks, of which the following is a specification, reference being had to the accompanying drawing, forming a part thereof.

The leading features of my design consist in a hammock, the body of which is provided with stripes composed of a series of diamond-shaped figures differentiated from the surrounding material, so as to catch the eye of the observer.

A A' represent broader stripes at the edges of the hammock-body, embellished with diamond-shaped figures B, and a represents narrower stripes intermediate of the broader stripes and, like the broader stripes, embellished with diamond-shaped figures B.

What I claim is—
